UNITED STATES PATENT OFFICE.

JOSEF CAYOT, OF OAKLAND, CALIFORNIA.

SELF-CLEANING SALT SHAKER AND THE LIKE.

Application filed March 25, 1926. Serial No. 97,209.

My invention relates broadly to shakers for salt, pepper, sugar and the like, and it has special reference to self-cleaning shakers and in which the material to be dispensed is also 5 agitated so as to prevent lumping therein.

In shakers of this class heretofore constructed, the material, even after being agitated, often clogs the perforations in the top of the shaker. The user is then obliged to resort to 10 pins or other slender objects for cleaning the perforations in order to effect the dispensation of the material from the shaker. Such pins or objects are not always at hand, and, even if they should be, it always takes some time before they can be brought into use for the aforementioned cleaning purpose. Much annoyance is in this way caused the users of the shakers and also embarrassment.

The principal object of my invention is to 20 provide a shaker of this class with means contained in the shaker for cleaning the perforations in the top thereof, and with means in the body of the shaker for agitating the material therein, so that the cleaning means and the 25 agitating means will always be at hand and thus the user of the shaker need lose no time in applying them.

Another object of the invention is to provide a shaker with a perforated top rotatably 30 mounted on the end of the body of the shaker and to mount within the shaker such means for cleaning the perforations as are operated simply by a rotative movement of the top.

A further object of the invention is to 35 mount loosely between the rotatable top of the shaker and the body of the shaker a perforated cleaning block provided with projections adapted to register with the perforations in the top, and to provide means carried 40 by the top for causing the block to rise, so that, when the top is rotated to one position, the projections will register with and pierce the perforations in the top for the cleaning thereof, and so that, when the top has been rotated 45 to another position, the material to be dispensed from the shaker will be permitted to pass through the perforations in the block and thence dispensed from the shaker through the perforations in the top.

50 A further object of the invention is to make the perforations in the top cone-shaped and to provide the cleaning block with cone-shaped projections adapted to be guided into and

then register with and pierce the perforations in the top for the cleaning thereof by a rotative movement of the top, so that the block is thereby prevented from binding in the top and thus the dispensing of the material from the shaker is always assured.

A still further object of the invention is to 60 mount upon the upper end of the body of a shaker a perforated top of a resilient material, and to provide the top with kerfs in the side walls thereof, so that the top can easily be slipped over and snapped onto or removed from the shaker and thereby access to the interior of the shaker is facilitated.

Other objects and advantages of my invention will be understood from the following 70 detailed description thereof and having reference to the preferred embodiment of the invention illustrated in the accompanying drawings, and in which:

Figure 1 is an elevation of a shaker constructed in accordance with my invention. Parts are shown in central, vertical section to show the relation of each to the other. In this view the shaker is shown as operable in the ordinary way, that is, shake it and the contents will sift from its top.

Fig. 2 is a view similar to Fig. 1 with the exception that the shaker top and the agitator secured thereto have been turned ninety degrees to effect a vertical movement of the cleaning block. The latter is shown in piercing engagement with the holes in the top.

Fig. 3 is a plan of the upper portion of the shaker as shown in Fig. 2.

Fig. 4 is an elevation of the top only, of 90 Fig. 3.

Fig. 5 is a plan of the cleaning block per se, and Fig. 6 is a central section through it.

Fig. 7 is a plan of the cleaning block seated upon its support. Part of the block is broken away to clearly show the plan of the opening 95 in the support.

Fig. 8 is an enlarged sectional view of a fragment of the shaker top and the cleaning block in engagement. These elements are shown as being formed of sheet material.

The numeral 10 indicates as a whole the present, preferred embodiment of my invention of a shaker for salt, sugar, pepper and the like. This shaker 10 comprises a container or body 11 of any suitable material, 105 such as glass, and is adapted to hold therein

the material to be dispensed, and the container is at its upper end provided with an open support 12, which may be made homogeneous with the container, or as a separate piece and secured thereto so as to be integral therewith. The support has peripherally formed thereon a curved or beaded portion 13, on which is adapted to fit snugly the curved or beaded portion 14 of a perforated top 15 made of a resilient suitable material, such as celluloid. The side walls of the top are provided with kerfs 16 so that resilient tongues 17 are thereby formed for snugly engaging the support and thus removably and 15 rotatably holding the top on the support.

Connected with the top and adapted to extend through the support and into the container 11, is an agitator 18 also of celluloid if desired, and it comprises a flat member having notched edges 9 for cutting and breaking the contents of the container. The agitator is provided with flanges 19 at its upper end just below the top of the support.

A cleaning block 21 having a central opening 22 therethrough loosely encompasses the neck 20 of the agitator, and upon the underside of the block a pair of cams 23 is provided for engagement by the flanges. The opening in the support is preferably cross-shaped, as 30 is most clearly shown in Fig. 7, so as to form edges 24 adapted to be engaged by the cams for holding the block in a non-rotative position. In the block are large perforations 25 for the unobstructed passage therethrough of the material to be dispensed, and the block has on its upper side projections 26, preferably cone-shaped and adapted to register with and to pierce the perforations in the top, and which perforations are preferably 40 also cone-shaped.

Normally, the cleaning block 21 is adapted by its own weight to rest on the top of the support 12, and, when it is desired to dispense the contents from the shaker 10, my improved shaker functions in the same manner as an ordinary shaker and permits its contents to pass through the perforations 25 in the block and thence through the perforated top. Should the perforations in the top 50 become clogged and require cleaning the user simply turns the top approximately ninety degrees on the support, thus causing the flanges 19 to engage the cams 23. The block will thereby be forced to rise and the projections 26, by means of their conical shape, will be guided into the corresponding conical perforations in the top, whereby registration and the consequent piercing of the perforations will be accomplished and the top 60 cleaned from the clogging material.

The cams have a sufficient play between the edges 24 of the opening in the support for allowing the block to be freely moved to or from its cleaning position, so that, when the 65 cleaning has been accomplished, the user by

again turning the top approximately ninety degrees releases the block from its cleaning position and thereby again restores the shaker to a condition for dispensing the material therefrom.

While I have shown the agitator as having a pair of flanges and the block as being provided with a corresponding pair of cams so that in such an instance it requires a rotative movement of approximately ninety degrees of the top for raising the block to the cleaning position, it is obvious that this arrangement is only illustrative and that I may provide the agitator with a different number of flanges and the block with a corresponding 70 number of cams, so that a rotative movement of the top of only a few degrees may be sufficient for moving the block to or from its cleaning position.

From the foregoing description taken in connection with the accompanying drawings the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be 90 made when desired, as fall within the scope of the appended claims.

Having thus described my invention, I claim as new and desire to secure by Letters Patent of the United States the following:

1. A shaker of the class described, comprising a container adapted to hold the material to be dispensed and provided with an open support at its upper end; a perforated top rotatably secured on the support; an agitator secured to the top and adapted to extend into the container and having flanges thereon; a cleaning block loosely mounted on the agitator and adapted to rest on the support and being provided with cams, the block having projections thereon adapted to register with and to extend into the perforations in the top for the cleaning thereof, and the block having openings therein for the passage therethrough of the material in the container, the cams being adapted to engage the edges of the opening in the support for holding the block in a non-rotative position, and the flanges being adapted to engage the cams for raising the block to the registering and cleaning position by a rotative movement of the top on said support.

2. In a shaker, the combination of a container having an open support at its upper end, a perforated top mounted on said container over said support, a cleaning block mounted for vertical movement between said top and said support, projections on the upper surface of said block and being adapted to register with the perforations in said top,

a cam on the underside of said block, and means secured to said top and engageable with said cam for raising said block to bring said projections into engagement with the

5 perforations when said top is rotated.

3. In combination, a receptacle, a cap revolvable thereon formed with dispensing perforations in a portion thereof, an element arranged for projection transversely of said

10 cap portion and into the perforations from without the same for cleaning the same, and means revolving with the cap operative to effect said projection of the said element.

4. In combination, a receptacle, a cap revolvable thereon formed with dispensing perforations, an element adapted for projection into the perforations from entirely without the same by and upon a rotative displacement of said cap for cleaning the perfora-

15 tions, and means revolving with the cap actuating the said element, the latter means including a member extending into and anchoring in loose material contained in the receptacle for yieldingly opposing revolving

20 motion of the cap.

5. In combination, a receptacle, a cap revolvable thereon formed with dispensing perforations in a portion thereof, an element arranged for projection transversely of said

25 portion and into the perforation for cleaning the same, means for limiting the motion of the element within the confines of the cap, and means revolving with the cap operative to effect said projection of said element.

6. In combination, a receptacle, a cap revolvable thereon formed with dispensing perforations, an element arranged for projection through the perforations axially thereof for cleaning the same, means holding the element against revolving motion, and means 40 revolving with the cap operative to actuate the said element by and upon a rotative displacement of the cap.

7. In combination, a receptacle having an open top formed to provide a seat, an element resting thereon formed with projections in the top thereof, a cap formed with perforations normally not registering with the projections, and means associated with the cap raising the said element when the cap is 50 turned to cause the perforations to register with the projections for projecting the latter into the former.

8. In combination, a receptacle having an open top formed to provide a seat, an element resting thereon formed with projections in the top thereof, a cap formed with perforations normally not registering with the projections, means associated with the cap raising the said element when the cap is 55 turned to cause the perforations to register with the projections for projecting the latter into the former, and means anchoring in loose material in the receptacle for yieldingly opposing revolving motion of the cap. 60

In testimony whereof, I affx my signature.

JOSEF CAYOT.
